COIN RECEPACLE

Roy V. Terry, Montclair, N. J., assignor to Bell Telephone Laboratories, Incorporated, New York, N. Y., a corporation of New York

Application August 3, 1935, Serial No. 34,482

21 Claims. (Cl. 232—15)

This invention relates to covers for coin boxes or receptacles and more particularly to covers for coin receptacles of the type used in telephone coin collectors, such a receptacle being described, for example, in United States Patent 1,121,063, issued December 15, 1914, to W. O. Beck.

An object of the invention is the prevention of fraudulent removal of the contents of coin receptacles.

10 Cash receptacles used in telephone coin collectors are ordinarily furnished with a hinged cover which has an opening therein through which the collected coins pass. A sliding shutter is usually provided for closing the coin receiving opening. A projection carried by an extension of the shutter is adapted to engage with a portion of the coin collector housing when the coin receptacle is placed therein, this engagement being effective, when the receptacle is being inserted in the housing, to move the shutter to open position and being effective, when the receptacle is being removed, to move the shutter to closed position. Means is ordinarily provided for automatically locking the shutter in closed position.

20 In accordance with the usual practice the empty coin receptacles are prepared for distribution at a central cashier's office. Before the cover is placed on the receptacle the locking means is set in free position, i. e., a position which allows the shutter to move to open position. The cover is now placed in position on the receptacle. The receptacles are then taken by designated employees to be placed in the coin collectors. As the receptacle is inserted in the housing the shutter is removed to open position as stated above and the locking means is ordinarily so arranged that just before the receptacle is fully inserted, the locking means is tripped and moved into locking position. Now when the filled receptacle is later withdrawn the shutter is closed as above mentioned, the locking means then being effective to hold the shutter in closed position.

30 According to a feature of the present invention the locking means is so arranged that it is protected against fraudulent operation by means of tools or otherwise.

40 In accordance with a specific embodiment of the invention the shutter locking means comprises a pawl mounted on the under side of the cover and operating in conjunction with teeth provided on an up-turned edge of an extension of the shutter plate. The pawl may be biased in either of two positions, locking or free, by a spring. When in locking position the pawl en-

gages with the teeth and prevents moving the shutter to the open position. The arrangement contemplated by the invention is such that the pawl is adequately protected against fraudulent operation by tools inserted in any manner through the openings in the cover. 5

In accordance with a modification of the invention automatically operating means are provided which serve to reset the locking pawl in free position as the cover is placed in closed position 10 on the associated coin receptacle.

A complete understanding of the operation of the receptacle cover contemplated by the invention and of the various advantageous features thereof may be gained from consideration of the 15 following detailed description and the annexed drawings in which:

Fig. 1 is a view of the underside of a coin receptacle cover of the type contemplated by the invention; 20

Fig. 2 is a view similar to that of Fig. 1, a part of the inner wall of the cover being broken away and one side wall of the pawl casing being removed to show the shutter and the arrangement of the locking pawl; 25

Fig. 3 is a plan view of the coin receptacle cover as the coin receptacle is being inserted in the coin collector, a part of the outer wall of the cover being broken away to show the position of the shutter; 30

Fig. 4 is an enlarged sectional view of the locking pawl and casing, the pawl being in free position; 35

Fig. 5 is a view similar to that of Fig. 4, the locking pawl being shown as it is tripped by the projection on the shutter;

Fig. 6 is a view similar to that of Fig. 4, the locking pawl being shown in locking position; 40

Fig. 7 is a side elevation of a portion of a coin receptacle and a coin receptacle cover, the cover being shown in partially closed position;

Fig. 8 is a side elevation of the locking pawl casing showing an automatic resetting mechanism for the pawl; 45

Fig. 9 is an exploded view of the automatic resetting mechanism shown in Fig. 8;

Fig. 10 is a sectional end view of the automatic resetting mechanism shown in Fig. 8, the plunger being shown in contact with a cam edge provided on the pawl casing; 50

Fig. 11 is a side elevation of the locking pawl casing showing another type of automatic resetting mechanism for the pawl;

Fig. 12 is an exploded view of the automatic resetting mechanism shown in Fig. 11; 55

Fig. 13 is a sectional end view of the automatic resetting mechanism shown in Fig. 11, the resetting pawl being shown moved out of engagement with the locking pawl;

5 Fig. 14 is an enlarged sectional view of a modified locking pawl and pawl casing, the locking pawl being shown in free position;

Fig. 15 is a view similar to that of Fig. 14, the locking pawl being shown in locking position;

10 Fig. 16 is a view similar to that of Fig. 14, the locking pawl being shown in contact with the outer edge of a tooth on the shutter; and

Fig. 17 is a plan view of a part of the shutter extension arm showing particularly the arrangement of the teeth and the tripping cam.

15 Referring now to the drawings and first to Figs. 1 and 2, a coin receptacle cover 21 is shown which is provided with a coin receiving opening 22 and a pivoted shutter 23 for closing said opening. The shutter is rotatably mounted on pivot 24, a bowed spring 25 being provided for normally holding the shutter in closed position. Two extension arms 26 and 27 are provided on shutter 23, arm 26 being provided with an upturned edge on which are formed teeth 31 and 32 and projection 33. Arm 27 extends upwardly from the inside of the cover through slot 34 to the outside of the cover and then laterally beyond the edge thereof as shown. A tripping cam 35 is also provided on extension arm 26. An inner wall 36 is fastened to the inside of the cover, acting as a protecting shield for the shutter and the other mechanism of the cover. Embossed portions 37 and 38 on wall 36 provide clearance for the teeth and projection 33 and for projection 35, respectively, when the shutter is rotated.

20 A rectangular casing 41 is mounted on inner wall 36, a locking pawl 42 being rotatably mounted within the casing on pivot 43. It will be noticed that the pawl is adapted to rotate in a plane at right angles to the plane of movement of the shutter. A projection 44 is provided at one end of the pawl which acts in conjunction with projection 35 on arm 26 to trip the pawl in a manner and for a purpose to be described subsequently. An aperture 45 is provided in the pawl, the purpose of which aperture will be subsequently described. One end of biasing spring 46 is attached to an end of pawl 42 while the other end is attached to casing 41.

25 While casing 41 is mounted on inner wall 36, end portions of the casing extend, as clearly shown in Fig. 2, to the outer wall 39 of the cover. Further, the side walls of the casing extend beneath inner wall 36, grooves 47 and 48 (Fig. 2) providing clearance for projection 35 and for the teeth and projection 33, respectively. It will be apparent from the above that the pawl is almost completely enclosed and is adequately protected against fraudulent operation by the arrangement of casing 41 and the cooperating walls of the cover. No space is provided, for example, for entry of a tool which might be inserted through coin leveling hole 49 or through coin receiving opening 22 in an attempt to move the end of the pawl out of its locking engagement with the teeth on arm 26.

30 Referring now to Fig. 3, the manner in which shutter 23 is moved to open position, as the coin receptacle is inserted in the coin collector housing, is illustrated. A portion 51 of the guide-rail, which is attached to the coin collector housing is shown, the guide-rail being provided, as shown, with an aperture 52 in which the end of arm 27 is positioned when the coin receptacle is

placed in the housing. Then, as the receptacle is pushed back into position in the housing in the direction indicated by the arrow, arm 27 is prevented from moving by the contact with the edge of aperture 52 so that the shutter is, in effect, moved to open position with respect to coin-receiving opening 22. Conversely, of course, when the receptacle is being moved in the opposite direction, that is, when it is being withdrawn from the housing, the shutter, is, in effect, moved to closed position with respect to opening 22. The respective dimensions and arrangement of the coin receptacle and the receptacle housing are such that it is impossible to insert the receptacle in the housing without first positioning arm 27 in aperture 52.

35 Before the receptacle is inserted in the housing, locking pawl 42 should be set in free position to allow shutter 23 to open. The pawl is shown in locking position in Fig. 2, one end of the pawl being in locking engagement with the edge of tooth 31. In order to move the pawl to free position, a suitable tool is inserted through aperture 55 (Fig. 4) provided in one of the side walls of casing 41 (this action taking place, of course, before the cover has been placed on the coin receptacle) and the pawl is rotated or tipped to the position shown in Fig. 4. Spring 46 acts to bias the pawl in whichever direction it may be rotated beyond the dead center position; the effective action of the spring in each position (Figs. 4, 5, and 6) being indicated by the respective arrows.

40 It will be noticed that in the position of Fig. 4, the pawl is free of the teeth carried on arm 26 and does not therefore interfere with the movement of the shutter. Projection 44 of the pawl is in contact with the opposite edge of arm 26, that is, the edge opposite to the teeth.

The pawl having been set in free position, the cover is placed on the coin receptacle and sealed after which the receptacle may be inserted in the coin collector. Now, as stated above, the shutter is opened as the receptacle is inserted in the housing (Fig. 3) until, when just short of the fully opened position (the approximate position illustrated in Fig. 3), projection 35 is brought into contact with projection 44 of the pawl and as the relative movement of the receptacle and the shutter continues, pawl 42 is rotated about pivot 43 by the camming action of projection 35 until the position shown in Fig. 5 is reached wherein, as shown, the opposite end of the pawl is in contact with projection 33. As indicated by the arrow, the biasing action of spring 46 is now in a direction opposite to that of Fig. 4. (The end of spring 46 is attached to pawl 42 at a point slightly below the horizontal center line so that the effective direction of the biasing action is as illustrated even though the pawl is approximately horizontal.)

45 The pawl remains in the position shown in Fig. 5 until the coin receptacle is removed from the coin collector housing. As the receptacle is being removed, shutter 23 is, in the manner previously described, moved to closed position with respect to coin opening 22. As the shutter moves in this direction, projection 33 is moved out of contact with the end of pawl 42, whereupon the pawl, due to the biasing action of spring 46, moves to the locking position shown in Fig. 6. As the shutter closes, the pawl rides up the inclined edges of teeth 31 and 32, dropping down back of the straight edge of each tooth as said tooth passes from under the pawl. During the closing motion

of the shutter three definite locking points are provided, therefore, one as the pawl drops back of projection 33, another as it drops back of tooth 32 and a third (shown in Figs. 1 and 6) as it drops back of tooth 31, this last position corresponding to the fully closed position of the shutter.

After the coin receptacle has been removed from the coin collector, the seal is broken by an authorized person and the cover removed from the receptacle. Before replacing the cover, the pawl is set in free position as before.

Referring now to Figs. 7 to 10, a modification of the invention is illustrated in accordance with which an automatic resetting mechanism for the locking pawl is provided. It will be remembered that in accordance with the arrangement just described, pawl 42 was manually set in free position by means of a suitable tool. In accordance with the present modification, however, the pawl is automatically set in free position as the cover is placed in position on the coin receptacle.

Referring first to Fig. 7, a coin receptacle cover 61 is shown being placed in position on coin receptacle 62. Cover 61 is, in general, similar to cover 21 previously described, being provided with an inner plate 63 and an outer plate 64 (Fig. 8) upon which plates is mounted a pawl casing 67. A pawl 68 (Fig. 9) is mounted within casing 67 and operates in a similar manner to that previously described in reference to pawl 42. Pawl 68 is, in fact, similar to pawl 42 the only essential difference being that, in the instance of pawl 68, an aperture 71 is provided therein. As shown in Fig. 9 an aperture is provided in one of the side walls of casing 67, an edge 72 of the aperture being beveled. An arm 73 is mounted on the side of casing 67 being rotatably supported on lug 74 (Fig. 9). The free end of arm 73 passes through slot 75 which is provided in one of the end walls of casing 67. A plunger 76 is positioned in sleeve 77, which is provided on arm 73, a spring 78 serving to bias plunger 76 in the direction of the pawl casing. A second spring 81 is associated with arm 73, one end of the spring being anchored in notch 82 (Fig. 9) and the other end passing through aperture 83, provided in lug 74, and resting against sleeve 77 as shown in Figs. 8 and 10. The spring acts to normally hold arm 73 in the position shown in Fig. 8.

Cover 61 is, like cover 21 previously described, provided with a coin receiving opening and a shutter, of similar arrangement and operating in a similar manner to that of shutter 23, for closing said opening. An extension 84 (Fig. 8) of the shutter which is similar in form to extension 26 previously described, is provided with a tripping cam 85 and two teeth and a projection (one tooth 86 being shown) which are similar, respectively, to tripping cam 35, teeth 31 and 32 and projection 33 previously described. A spring (not shown) acts in a manner similar to that of spring 46 previously described to bias pawl 68 either in locking or free position.

Assuming now, in order to illustrate the operation of the automatic resetting mechanism, that pawl 68 is in locking position and that cover 61 is about to be placed in position on receptacle 62. Arm 73 is held in the position shown in Fig. 8 by the action of spring 81 and tip 87 (Fig. 9) of plunger 76 is positioned in aperture 71 of pawl 68, spring 78 acting, as pointed out above, to force plunger 76 towards pawl 68.

Now, as cover 61 is closed, the free end of arm 73 is brought into contact with projection 91 provided on an end wall of the receptacle (Fig. 7)

which contact causes, in effect, movement of arm 73 about lug 74 in a direction approaching wall 63. As arm 73 is moved in this direction, pawl 68 is rotated in the same direction, due to the engagement of projection 87 in aperture 71, until the pawl reaches its free position. Now as the movement of arm 73 continues, the edge of plunger 76 is brought into contact with beveled edge 72 which contact is effective to cam plunger 76 back against the action of spring 78 so that, as shown in Fig. 10, tip 81 is withdrawn from aperture 71 of pawl 68. Pawl 68, which is now in free position being biased and held therein by the action of the biasing spring previously referred to, is therefore released from any restraining force of the resetting mechanism and may be tripped into locking position as above described. (In view of the fact that pawl 68 is tripped into locking position during movement of the shutter to the open position in the same manner as pawl 42 previously described it is not thought necessary to again describe this operation in detail.)

After receptacle 62 has been removed from the coin collector housing and as cover 61 is removed from the receptacle, arm 73, being freed from contact with projection 91, is returned by the action of spring 81 to the position shown in Fig. 8. As this position is reached, tip 81 again enters aperture 71 in locking pawl 68 (now in locking position) and the resetting mechanism is again in position to reset the pawl when the cover is subsequently placed in position on the coin receptacle and closed.

Referring now to Figs. 11 to 13, a modification of the automatic resetting mechanism just described is disclosed. Here again we have a coin receptacle cover, similar to cover 21 previously described, including an inner plate 95 and an outer plate 96. As before, a coin receiving opening is provided in the cover with a shutter, similar to shutter 23, for closing the opening. An extension 97 of the shutter (Fig. 11) corresponds to extension 26 of shutter 23 and is provided with a tripping cam 98 similar to cam 35, a projection similar to projection 33 and two teeth (one 99 being shown) similar to teeth 31 and 32.

A pawl casing 101 is mounted on the cover, a locking pawl 102 (Fig. 13) being mounted within the casing. This pawl is similar, and functions similarly, to pawls 42 and 68 previously described and is, like pawl 68, provided with an aperture 103, (corresponding to aperture 71). The pawl is provided, as were pawls 42 and 68, with a spring (not shown) for biasing it in either the free or locking position. An arm 103 is mounted on the side of casing 101 being rotatably supported on lug 104. The free end of arm 103 passes through slot 109 which is provided in one end wall of casing 101. A resetting pawl 105 is rotatably mounted on lug 106 (Fig. 12) by pin 107 which is positioned in apertures 111 and 112. Tip 113 of pawl 105 passes through aperture 114 in arm 103 and aperture 119 in the side of casing 101. Spring 115 is associated with arm 103, one end being anchored in slot 109 and the free end passing through aperture 117 of lug 104 and being positioned in aperture 118 of resetting pawl 105. Spring 115 acts to hold arm 103 in the position shown in Fig. 11 and also tends to rotate resetting pawl 105 in a direction to bring tip 113 into contact with locking pawl 102.

The operation of the mechanism is, in general, similar to that of the arrangement illustrated in Figs. 7 to 10, the mechanism being in the position shown in Fig. 11 before the cover is placed in position on the coin receptacle. In the position

- of Fig. 11, tip 113 of resetting pawl 105 is engaged with aperture 108 of locking pawl 102, spring 115 acting, as previously mentioned, to so bias pawl 105 that tip 113 is urged towards locking pawl 102. 5 Now, when the cover is closed, arm 103 is rotated in the manner previously described in reference to arm 73, locking pawl 102 being rotated in the same direction due to the action of resetting pawl 105 until said locking pawl snaps into its free 10 position. As movement of arm 103 continues, tip 113 is brought into contact with the edge of aperture 119, this contact being effective to so rotate resetting pawl 105 against the force of spring 115 that tip 113 is, as shown in Fig. 13, withdrawn 15 from aperture 108 of locking pawl 102. Locking pawl 102 is therefore freed of any restraining force by the resetting mechanism.

In the manner before described, the resetting mechanism returns to the normal position (Fig. 20 11) when the cover is removed from the receptacle, tip 113 of resetting pawl 105 thereupon re-entering aperture 108 of locking pawl 102.

Referring now to Figs. 14 to 17, a modified form 25 of the locking arrangement is disclosed. In accordance with the present modified form, locking pawl 121 is mounted vertically in pawl casing 122 whereas, in the form first described, locking pawl 42 was mounted horizontally in its casing. So far as the general arrangement of the cover and 30 shutter and their operation is concerned, however, the present modification is similar to the embodiment previously described and illustrated so it is not considered necessary to again illustrate or describe in detail the features common 35 to both forms.

In accordance with the modification, pawl 121 is 40 rotatably supported on pivot 123 which is, in turn, supported by the side walls of pawl casing 122. Casing 122 is mounted on inner plate 124 and outer plate 125 of the cover in a manner 45 similar to that in which casing 41 is mounted. Spring 126 is supported by the end walls of casing 122 and acts in conjunction with the tip of pawl 121 to bias said pawl in whichever direction beyond the point of dead center it is moved. An 50 aperture 131 is provided in one side of pawl casing 122 through which a suitable tool may be inserted to manipulate the pawl, the end of the tool being positioned for this purpose in aperture 132 of the pawl.

While as previously stated the operation and 55 general arrangement of shutter 133 is similar to that of shutter 23 previously described, the arrangement of extension arm 134 (Fig. 17) differs somewhat from that of the corresponding part (extension arm 26) of the form first described. In the present case, teeth 135, 136 and 137 are 60 embossed on up-turned edge 141 of the shutter while tripping cam 142 is embossed on up-turned edge 143.

The operation of the present locking arrangement is similar, in general, to that previously described. Let us assume, for example, that the coin receptacle is being inserted in the coin collector housing, the cover being, of course, in closed position and locking pawl 121 being set in free position as shown in Fig. 14. Shutter 133 is moved to open position as the receptacle is inserted in the housing in the manner previously described, projection 142 (Fig. 17) being brought into engagement with the edge of pawl 121. As movement of the shutter continues, projection 142, in passing pawl 121, causes rotation of said pawl against the action of spring 126, 75 to the locking position shown in Fig. 15. As

shown in this figure pawl 121 rests in contact with up-turned edge 141 of extension 134.

Now as the receptacle is subsequently removed from the housing, shutter 133 is moved to closed position in the manner previously described, pawl 121 riding over the sloping edges of teeth 135, 136 and 137 but remaining as shown in Fig. 16 (the arrows in Figs. 14, 15 and 16 indicating the biasing direction of spring 126) biased in the locking direction so that, as each successive tooth is passed, the pawl snaps behind the face thereof thereby providing three definite locked positions as in the instance of the form previously described. After the cover has been removed from the receptacle, pawl 121 may be reset in the free position of Fig. 14 by means of a tool of the nature previously referred to.

It will be understood that the general mounting arrangement of pawl casing 122 is similar to that previously described in reference to casing 41 so that the locking pawl in the present instance also is adequately protected against fraudulent manipulation.

While certain specific embodiments of the invention have been selected for detailed description, the invention is not limited in its application to the embodiments described. The embodiments described should be taken as illustrative of the invention rather than as restrictive thereof.

What is claimed is:

1. A coin receptacle comprising a box, a cover therefor having a coin receiving opening therein, a shutter on said cover for closing said opening, teeth on said shutter, a pawl rotatably mounted on said cover for co-operating with said teeth to hold said shutter in closed position and means in addition to said cover for substantially completely enclosing said pawl.

2. A coin receptacle comprising a box, a cover 40 therefor having a coin receiving opening therein, a shutter on said cover for closing said opening, an extension on said shutter, one edge of said extension being approximately perpendicular to the surface of said extension and shutter, 45 teeth on said edge, a pawl rotatably mounted on said cover for co-operating with said teeth to hold the shutter in closed position and means in addition to said cover for substantially completely enclosing said pawl.

3. A coin receptacle comprising a box, a cover therefor having a coin receiving opening therein, a shutter on said cover for closing said opening, teeth on said shutter, a casing mounted on said cover and a pawl rotatably mounted within said casing for co-operating with said teeth to hold said shutter in closed position.

4. A coin receptacle comprising a box, a cover therefor having a coin receiving opening therein, a shutter on said cover for closing said opening, teeth on said shutter, a casing mounted on said cover, a pawl rotatably mounted within said casing, means for biasing the pawl in either of two positions, the pawl being in contact with said teeth in one of said positions and being free of said teeth in the other of said positions and means carried by said shutter for causing movement of said pawl from the free position to the engaging position.

5. A coin receptacle comprising a box, a cover 70 therefor having a coin receiving opening therein, a shutter on said cover for closing said opening, teeth on said shutter, a casing mounted on said cover, a pawl rotatably mounted within said casing, means for biasing the pawl in either of two 75

positions, the pawl being in contact with said teeth in one of said positions and being free of said teeth in the other of said positions and means carried by said shutter for causing movement of 5 said pawl from the free position to the engaging position, said last mentioned means being effective to cause said movement of the pawl during movement of the shutter from closed position to open position and said shutter reaches its fully 10 opened position.

6. A coin receptacle comprising a box, a cover therefor having a coin receiving opening therein, a shutter on said cover movable from a position closing said opening to a position unobstructing 15 said opening, teeth on said shutter, a pawl rotatably mounted on said cover movable in a plane perpendicular to the plane of movement of the shutter, means for biasing the pawl in either of two positions, the pawl being in contact with said teeth in one of said positions and being free of said teeth in the other of said positions, and means carried by said shutter and effective upon movement thereof from said closing 20 position to said unobstructing position for causing movement of the pawl to said engaging position.

7. A coin receptacle comprising a box, a cover therefor having a coin receiving opening therein, a shutter on said cover for closing said opening, 30 teeth on said shutter, a pawl rotatably mounted on said cover for cooperating with said teeth to hold the shutter in closed position, and means for biasing said pawl in either of two positions, said pawl being movable in a plane perpendicular to the plane of movement of the shutter.

8. A coin receptacle comprising a box, a cover therefor having a coin receiving opening therein, a shutter on said cover for closing said opening, teeth on the shutter, a casing mounted on said 40 cover and a pawl rotatably mounted within said casing for co-operating with said teeth to hold the shutter in closed position, said casing having an aperture therein through which a tool for manipulating the pawl may be inserted.

45 9. A coin receptacle comprising a box, a cover therefor having a coin receiving opening therein, a shutter on said cover for closing said opening, an extension on the shutter, one edge of the extension being approximately perpendicular to the 50 surface of said extension and shutter, teeth on said perpendicular edge, a casing mounted on the cover, a pawl mounted within the casing movable in a plane perpendicular to the plane of movement of the shutter, a spring for biasing the pawl in either of two positions, the pawl being in contact with said teeth in one of said positions and being free of said teeth in the other position, said casing having an aperture therein through which means to move the pawl to said free position may 55 be inserted and a projection on the shutter for causing movement of the pawl to said contacting position.

60 10. A coin receptacle comprising a box, a cover therefor having a coin receiving opening therein, a shutter on said cover for closing said opening, teeth on said shutter, a pawl rotatably mounted on the cover for cooperating with said teeth to hold the shutter in closed position, said pawl being movable in a plane perpendicular to the plane 65 of movement of the shutter, means for limiting the rotation of the pawl in each direction and means effective upon rotation of the pawl in either direction from the dead center position for biasing the pawl in that direction.

75 11. A coin receptacle comprising a box, a cover

therefor having a coin receiving opening therein, a shutter on said cover for closing said opening, teeth on said shutter, a pawl rotatably mounted on the cover for cooperating with said teeth to hold the shutter in closed position, said pawl being movable in a plane perpendicular to the plane of movement of the shutter, means for limiting the rotation of the pawl in each direction and a bowed spring effective upon rotation of the pawl in either direction from the dead center position for biasing the pawl in that direction. 5

12. A coin receptacle comprising a box, a cover therefor having a coin receiving opening therein, a shutter on said cover for closing said opening, 15 teeth on said shutter, a pawl rotatably mounted on said cover for cooperating with said teeth to hold the shutter in closed position, said pawl being movable in a plane perpendicular to the plane of movement of the shutter, means for limiting 20 the movement of the pawl in each direction and means for biasing the pawl in whichever direction it may rotate with respect to its horizontal axis.

13. A coin receptacle comprising a box, a cover 25 therefor having a coin receiving opening therein, a shutter on said cover for closing said opening, teeth on said shutter, a casing mounted on said cover, a pawl rotatably mounted in said casing for cooperating with said teeth to hold the shutter 30 in closed position and means for biasing said pawl, said biasing means being effective upon movement of the pawl in one direction from its normal horizontal axis to bias said pawl in that direction and being effective when the position of 35 said pawl coincides with its normal horizontal axis or upon movement of the pawl in the direction from its normal horizontal axis opposite to the first mentioned direction to bias said pawl in said opposite direction. 40

14. A coin receptacle comprising a box, a cover therefor having a coin receiving opening therein, a shutter on said cover for closing said opening, an extension on the shutter, one edge of the extension being approximately perpendicular to the 45 surface of said extension and shutter, teeth on said perpendicular edge, a casing mounted on the cover, a pawl mounted within the casing, a spring for biasing the pawl in either of two positions, the pawl being in contact with said teeth in one of said positions and being free of said teeth in the other position, said casing having an aperture 50 therein through which means to move the pawl to said free position may be inserted and a projection on the shutter for causing movement of the pawl to said contacting position. 55

15. A coin receptacle comprising a box, a cover therefor having a coin receiving opening therein, a shutter on said cover for closing said opening, teeth on said shutter, a casing mounted on said cover, a pawl rotatably mounted in said casing for cooperating with said teeth to hold the shutter in closed position, means for limiting the movement of the pawl in each direction and means for biasing the pawl in whichever direction 60 it may rotate with respect to its vertical axis.

16. A coin receptacle comprising a box, a cover therefor having a coin receiving opening therein, a shutter on said cover for closing said opening, a projection on said shutter, a pawl mounted on 70 said cover for co-operating with said projection to hold the shutter in closed position, means for biasing the pawl in either of two positions, the pawl being in the path of the projection in one of said positions and being out of the path of the 75

projection in the other of said positions and means, effective upon the cover being placed in closed position on the box, for causing movement of the pawl to said other position.

5 17. A coin receptacle comprising a box, a cover therefor having a coin receiving opening therein, a shutter on said cover for closing said opening, a projection on said shutter, a pawl mounted on said cover for co-operating with said projection 10 to hold the shutter in closed position, means for biasing the pawl in either of two positions, said pawl being effective in one position to cooperate with said projection to hold the shutter closed and being ineffective in the other position to hold 15 the shutter closed, means carried by the shutter for causing movement of said pawl from the ineffective position to the effective position and additional means, effective upon the cover being placed in closed position on the box, for causing 20 movement of said pawl from the effective position to the ineffective position.

18. A coin receptacle comprising a box, a cover therefor having a coin receiving opening therein, a shutter on said cover for closing said opening, 25 means for holding said shutter in closed position, means for biasing said holding means in either of two positions, said holding means being effective to hold the shutter closed in one of said positions and being ineffective to hold the shutter 30 closed in the other of said positions, means, effective as the cover is being placed in closed position on the box, for engaging said holding means and moving it to the ineffective position and additional means, effective after the holding means 35 has been moved to the ineffective position and before the cover has reached the fully closed position on the box, for causing disengagement of said holding means and said moving means.

19. A coin receptacle comprising a box, a cover 40 therefor having a coin receiving opening therein, a shutter on said cover for closing said opening, an extension on the shutter, one edge of the extension being approximately perpendicular to the surface of said extension and shutter, teeth on 45 said perpendicular edge, a casing mounted on the cover, a pawl mounted within the casing movable in a plane perpendicular to the plane of movement of the shutter, a spring for biasing the pawl in either of two positions, the pawl being in contact with said teeth in one of said positions and being free of said teeth in the other position, said casing having an aperture therein, said pawl also having an aperture therein, an arm rotatably mounted on said casing, a plunger slidably mounted on said arm, means for causing engagement of the plunger and the aperture in said pawl when the arm is in normal position and when the pawl is in said contacting position, means, com-

5 prising a projection on a wall of said box, for so moving the arm and plunger when the cover is being placed in closed position on the box that the engagement of the plunger and the aperture in the pawl is effective to move the pawl to said free position and additional means, comprising a beveled surface on one of the defining walls of said aperture in the casing, for causing disengagement of said plunger and said pawl after the pawl 10 has reached said free position.

10 20. A coin receptacle comprising a box, a cover therefor having a coin receiving opening therein, a shutter on said cover for closing said opening, an extension on the shutter, one edge of the extension being approximately perpendicular to the surface of said extension and shutter, teeth on 15 said perpendicular edge, a casing mounted on the cover, a pawl mounted within the casing movable in a plane perpendicular to the plane of movement of the shutter, a spring for biasing the pawl in either of two positions, the pawl being in contact with said teeth in one of said positions and being free of said teeth in the other position, said casing having an aperture therein, said pawl also having an aperture therein, an arm rotatably mounted on said casing, a second pawl rotatably mounted on said arm, means for causing engagement of an end of said second pawl and the aperture in said first mentioned pawl when said arm is in normal position and when said first mentioned pawl is in said contacting position, means, comprising a projection on a wall of 20 said box, for so moving said arm and said second pawl when the cover is being placed in closed position on the box that the engagement of said second pawl and the aperture in said first mentioned pawl is effective to move said first mentioned pawl to said free position and additional means, comprising one of the defining walls of said aperture in the casing, for causing 25 disengagement of said second pawl and said first mentioned pawl after said first mentioned pawl has reached said free position.

30 21. A coin receptacle comprising a box, a cover therefor having a coin receiving opening therein, 40 a shutter on said cover for closing said opening, an extension on said shutter, two edges of said extension being approximately perpendicular to the surface of the shutter and extension, teeth on one of said edges, a pawl, means for biasing the pawl in either of two positions, the pawl being in contact with said teeth in one of said positions and being free of said teeth in the other of said positions, and means on the other of said edges for causing movement of said pawl from the free 45 position to the contacting position.

50 ROY V. TERRY.
